UNITED STATES PATENT OFFICE.

CHARLES M. WEYMANN, OF SAN FRANCISCO, CALIFORNIA, ASSIGNOR TO
THE CAHILL & HALL ELEVATOR COMPANY, OF SAME PLACE.

ELECTRIC ELEVATOR-CONTROLLER.

SPECIFICATION forming part of Letters Patent No. 595,086, dated December 7, 1897.

Application filed January 27, 1897. Serial No. 620,880. (No model.)

To all whom it may concern:

Be it known that I, CHARLES M. WEYMANN, a citizen of the United States, residing in the city and county of San Francisco, State of California, have invented an Improvement in Electric Elevator-Controllers; and I hereby declare the following to be a full, clear, and exact description of the same.

My invention relates to a means for controlling the movements of electrically-actuated motors, especially when connected with elevators, and which I call an "electric elevator-controller."

It consists in certain details of construction which will be more fully explained by reference to the accompanying drawings, in which—

Figure 1 is a diagrammatic view of my apparatus. Fig. 2 is a vertical section of elevator. Fig. 3 is a view of the switchboard. Fig. 4 is a plan view of the controlling mechanism. Fig. 5 is an elevation of the solenoids and connections. Fig. 6 is a vertical section through the clutch mechanism and its connections. Fig. 7 is a view of the switch-points and dial-arms. Fig. 8 shows the cut-off mechanism for the small motor. Fig. 9 is a section showing one of the yielding contacts.

The object of my invention, as herein described, is to provide a means for perfectly controlling the movements of an electric motor when subjected to a varying load, as illustrated in the operation of an elevator.

In carrying out my invention I employ a mechanism by which I first establish the direction in which the elevator-cage is to move. At the same time I energize a magnetic clutch and finally start a mechanism which serves to connect the electrical circuit through the fields and armature of the motor and to regulate the amount of resistance in the circuit to suit the varying character of the load to be moved. I have also shown an automatic mechanism for cutting the current off from the motor which actuates the magnetic clutch and connected mechanism.

A is the cage of an elevator, adapted to travel in the usual guides, having a suspending and elevating rope or connection at B and a motor located at C, which actuates the rope-winding mechanism of the elevator. The lat-

ter, forming no part of my invention, is not here shown.

Within the elevator-cage is a switchboard consisting of a semicircle D, which is connected with the main-line wire D' and smaller contact-segments E E' and F F'. A lever-arm G is pivoted centrally within these segments and is movable by a suitable handle, so as to contact with and make connection between the various segments of the switchboard, as may be desired.

At any suitable point with relation to the elevator is situated the mechanism of my controlling apparatus, which may be inclosed in a suitable casing B'. The various lines of wire from the switchboard just previously described may pass through a cable h to a junction-box H and from thence to the controlling mechanism. Fig. 1 is a diagrammatic view of this apparatus.

Within the casing B' are fixed solenoids consisting of two coils J J', each having a core K, either of which will be drawn into its solenoid whenever the latter is energized. These cores are connected with short crank-arms L, which project upon opposite sides of a shaft M, suitably journaled with reference to the solenoids, so that whenever this shaft is turned to one side or the other one of the cores K will be moved into its solenoid and the other simultaneously withdrawn. This movement takes place when one of the solenoids is energized, and this one establishes the direction the motor and the elevator-cage are to be run, as follows: Upon the end of the shaft M is a non-conducting lever-arm N, carrying suitable contacts O O', which are connected by flexible wires O² O³ with binding-posts O⁴ O⁵, so as to allow the lever to move freely. The binding-posts are connected by wires P P' with the main-motor armature. The movement of the lever N throws it into contact either with the points P² and P³ or P⁴ and P⁵, and thus establishes a circuit either through the wire P and return through P', by which the motor will be driven in one direction, or through the wire P' and return through P, which will serve to drive it in the opposite direction. This establishing of the direction in which the motor is to move is made by the movement of the lever G. If

- it be thrown over so as to establish communication through the segment E on the switchboard within the cage, a circuit will be established from the main line through 5 wire Q to the solenoid J and by the wire R to main line, which will first energize the solenoid J, thus attracting its core and drawing it into the solenoid, and through the lever L the shaft M and the lever-arm N will be 10 moved, so as to produce the connections which will establish the circuit through the main-motor-armature wires P P', so that the direction of movement of the motor and that of the elevator-cage is established. The current 15 passing through the solenoid also passes through a connecting-wire R to a magnetic clutch S. This clutch is of any usual well-known construction and is shown in the present case as consisting of two concentric 20 members movable about a common axis with relation to each other. The outer shell S of this clutch is mounted upon a sleeve T, and this sleeve T has fixed upon it a worm-wheel U, which is adapted to be engaged by a worm 25 or screw U', so that when the latter is turned it will rotate the worm-gear U and connected parts. This screw U' is actuated by a small motor V, which is energized as hereinafter described. The sleeve T and the parts carried 30 by it turn loosely upon an inner shaft T', suitably journaled, and this shaft carries the other member S' of the clutch. The coil by which the clutch is magnetized is contained within the outer casing S of the 35 clutch, and when energized it serves to hold the part S' with relation to the part S so that when the worm-wheel U is turned and the part S of the clutch is rotated thereby the part S' will be moved with the outer casing 40 of the clutch and will thus turn the interior shaft T'. Upon this shaft is fixed a double dial-arm W W', which is movable with the shaft, the part W moving over the independent switch points or plates Y of a segmental 45 are fixed with relation to this arm, as shown. The part W' of this dial-arm moves over the plates Y' of a second segment of smaller diameter, fixed upon the opposite side of the journal-shaft of the dial-arm. The plates Y 50 are connected with a series of resistance-coils Z, and the plates Y' are correspondingly connected with a series of resistance-coils Z'. The upper and lower contact-plates are connected by means of the dial-arm W W', as hereinafter described. The resistance-coils Z are 55 in series with the armature of the main motor and the resistance-coils Z' with its shunt-field. The operation of this portion will then be as follows:
- 60 The normal position of the dial-arm is, as shown in the present case, vertical and lying between the two segments Y and Y' before the dial-arm commences to turn by the connecting of the motor, and when in this position no electrical current can pass through the main motor. The small motor V is connected (after the direction has been established and

the clutch energized, as previously described) by moving the lever G until it contacts with the plate F of the switchboard in the cage. 70 This makes connection between the main-line wire and the wire a, which connects with the small motor V and sets it in motion. The movement of this motor V is always in the same direction, and, as previously described, 75 it acts through the worm U' and worm-wheel U to move the clutch S S' and the dial-arm W W'. The first movement of this dial-arm connects up the field-circuit by contact of the lower end W' with the first of the plates Y', 80 and a further movement connects the end W with the first of the plates Y. After these two contacts are formed the circuit is complete and permits the passage of the current through both field and armature. The current 85 passes first to the junction of the shunt and series field, dividing, one part passing through the shunt-field at C, thence to lower contact Y', thence through the connection y from Y' to Y. The other part of the current 90 passes through the series field, thence to P² O O² P', thence through the armature of large motor, thence through P O³ O' P³, thence through P⁵ P⁴, thence through resistance-coil Z to upper contact Y, uniting at that point 95 with the shunt-circuit, and as soon as the dial-arm has touched the first contact of Y, when both fields and armature are energized, the circuit then passes through the return-wires of the circuit. The full amount of the 100 resistance is at this time connected with the armature, and, correspondingly, the least resistance in the shunt-field. As the dial-arm W W' moves successively over the plates Y Y' the resistance in the armature-circuit 105 is decreased and that in the shunt-field circuit is increased until the dial-arm has made very nearly a half-revolution, so that the ends are very nearly reversed and the resistance in the armature cut out and that in the 110 fields increased to its maximum, thereby giving the maximum speed of the main motor. The shaft T', which carries the dial-arm, extends through the back of the case containing the mechanism and upon the rear carries a crank-arm b. This crank-arm turns with the movement of the shaft T' until it contacts with the forked or Y-shaped arm c, which is pivoted, as shown at c', at the junction of its arms. The arm b striking one 115 of the arms c turns it and breaks the circuit to the small clutch-actuating motor V, and this prevents any further movement of the dial-arm in this direction. The shaft T' carries on its end the longer arm b and the shorter 120 arm b'. The longer arm is also preferably set out a little, so as to clear the stop b², which latter is, however, not essentially necessary, as the weight and rope regulate the amount of travel of the shaft T'. The arm c' is also 125 a trifle shorter than the arm c. In Fig. 8 the arm c is shown as just pushed outwardly by the arm b, and this separates the arm c' from the contact a' and opens the main circuit. At

the same time it brings the arm c' into the path of travel of the arm b , so that on its return the arm b will strike the arm c' , thereby closing the circuit again. The arm b' , being 5 shorter, will clear the arms c and c' , but will strike the stop b^3 on the forward movement, the arm c' having been pushed out of the way of arm b , but arm c stands in its line of travel, so that arm b will pass arm c' and will strike 10 arm c . Connection is made as follows: A positive current through the wire D' passes through G on the cage, thence through F , thence through the wire a , thence through the axis of arm c' , thence to contact-point 15 with arm b , thence through the small motor which operates the dial, and thence out. When the dial turns around, it cuts the circuit out.

If no change in the speed of the main motor 20 is desired, the dial-arm W may remain in the position last described, where the speed of the main motor will be the greatest; but if it is desired to reduce the speed of the cage it is done by deenergizing the clutch S by 25 the movement of the cage-lever G . As soon as the clutch is deenergized the dial-arm W is returned to its normal position or to any point between the extremes by the action of a weight d , attached to a cord e , which passes 30 around a pulley f , fixed upon the shaft T' in such a manner that the weight acts in opposition to the clutch, and this weight is sufficient when the clutch is deenergized to rotate the shaft T' in the opposite direction to which 35 it is moved by the clutch, thus returning the dial-arm to its normal position, as previously described. By reenergizing the clutch at any time it will stop and hold the dial-arm W at any intermediate point desired. 40 In order to abruptly break the connection between the dial-arm and its contacts as it returns, I have shown the arm as forming a hinged or pivoted extension g , so attached that when the dial-arm is moving forward 45 over the contacts by reason of the action of a clutch this extension, resting against a stop g' , remains rigidly in line with the remainder of the arm, and the yielding contact-point h is forced back to allow the arm g to 50 pass it. This contact-point h passes through the back and is connected by a flexible wire with the first contact-plate of the series of resistance-coils. When the dial-arm returns, and just before it reaches its normal position, 55 the extension g contacts with the point h . The extension g , which is normally kept in line with the remainder of the dial-arm W by a light spring, will yield when it contacts with the projection h , and this will allow the extension 60 to turn about its joint, maintaining the contact between the end of the extension and the point h , through which the circuit is completed, until the dial-arm W has moved to a point which will cause the extension g to 65 pass the point or stop h , which has hitherto formed contact with it, and the extension is then suddenly released and by the action of

its spring is disengaged from the contact-point and returned into line with the dial-arm W . This breaks the circuit abruptly and 70 prevents damage to the parts by being burned by the current at the instant of breaking the circuit.

If the cage is at the top and has to come down, the lever G in the cage will be moved 75 to contact with the point E' , and this connects, through the wire P' , and returns through P , with the solenoid J' , which is thus energized, so as to draw its core K into it, and, acting, as previously described, upon the shaft M and 80 lever N , will throw the latter over, so as to engage the contacts P^4 and P^5 , thus giving a direction to the main motor which will allow the cage to descend. The clutch S is also energized at the same time through the connect- 85 ing-wire R , as before described, and a further movement of the cage-lever G forms contact with the plate F , and through the circuit of the wire a the small motor V is set in motion and the dial-arm W is moved over the contacts Y Y' , through which the resistance-coils are controlled, and the operation will be the same as previously described.

If the weight of the cage is so great as to overcome the power of the motor when the 95 dial-arm W has moved so far as to cut out a great portion of the resistance, the clutch is demagnetized and the dial-arm returned by the weight d to its normal position, thus increasing the resistance of armature and decreasing the resistance of shunt-field, causing a strong field which will decrease the speed of the main motor. When the dial-arm is in its normal position, the lower end W' will rest against a pin k , which is connected by a wire 100 k' with some plate Y' of the shunt series, (preferably with the second.) By means of this connection the external circuit is cut out and a reconnection is made with the shunt-circuit. The current passes through the field-magnet to lower contact Y' , thence through K' to K , thence to W' , to upper contact Y , to 105 P^4 , to P^3 , O' , O^3 , and P , through the motor C , thence through P' to O^2 , to O P^2 , and back to the field-magnet, thus completing the inside 110 circuit. This takes place when the pointer shown in Fig. 7 has moved into the vertical position, where it makes contact at the point K . This prevents injurious discharges of the field-circuit and permits the motor to be instantaneously turned into a generator without detrimental results. When the motor is thus 115 changed to a generator, it acts to control the movement of the cage by its resistance, and more especially when the cage is descending 120 with a heavy load.

By this device I provide a perfect controlling mechanism for all the movements of the motor and the elevator which it controls.

Having thus described my invention, what 130 I claim as new, and desire to secure by Letters Patent, is—

1. The combination with an electric motor and an elevator mechanism moved thereby,

- of a mechanism comprising solenoids having movable cores and mechanism actuated by the cores whereby contacts are produced and the direction of the motor first established,
- 5 a controlling device whereby both armature and field resistance are varied proportionately to the desired motor-speed, and an automatically-operating device comprising an electric clutch within the circuit which is established
- 10 through the solenoids and intermediate mechanism whereby the controller is disengaged and returned to its normal position.
2. The combination with an electric motor, resistance-coils having one end connected
- 15 with the armature and the other end to the field of the motor, a dial-arm forming a switch-contact movable over the contact-points which are connected with the resistance so that the resistances in the field and armature circuits
- 20 are varied inversely, and an automatically-operating mechanism comprising an electric clutch and intermediate mechanism connecting the clutch with the dial-arm whereby the dial-arm is moved.
- 25 3. The combination with an electric motor and an elevator-cage driven thereby, of a mechanism whereby contacts are produced and the direction of motion of the motor is first established, comprising solenoids having
- 30 movable cores, and mechanism connected therewith and actuated by one or the other of the cores in opposite directions whereby the contacts are formed to establish the direction of the motor, an electric clutch within
- 35 the circuit which is established through the solenoids which is energized at the same time the direction of rotation of the motor is established, and connections between the solenoids and the cage whereby either of them is
- 40 energized.
4. The combination with an electric motor and mechanism driven thereby, of resistance-coils connecting respectively with the armature, and the fields of the motor whereby the
- 45 resistance of the electric current through the motor is varied, a dial-arm movable over and forming contact successively with switch-points whereby the resistance-coils are thrown into or out of the circuit and an electric clutch
- 50 and intermediate mechanism whereby the clutch engages and moves the dial-arm or is disengaged therefrom to allow the dial-arm to return to its normal position.
5. The combination with an electric motor
- 55 and mechanism driven thereby, of resistance-coils, a mechanism whereby said coils are thrown into or out of the circuit, consisting of switch points or segments connecting respectively with the armature and field resist-
- 60 ance-coils, a dial-arm pivoted so as to move over the segments and successively throw in or cut out the resistance-coils, an electric clutch connecting with the shaft by which the dial is turned, means for energizing and
- 65 deenergizing the clutch, a mechanism by which the clutch is rotated when energized and the dial-arm carried thereby, and means

for returning the dial-arm to its normal position when the clutch is deenergized.

6. The combination with an electric motor 70 and mechanism driven thereby, of resistance-coils connecting respectively with the armature and fields of the motor, switch-points arranged in segments, one series being connected with the armature and the other with 75 the field-circuit, a dial-arm pivoted centrally with relation to the segments and movable over them so that one end passes over the armature - resistance switch - points, and the other over the field-resistance switch-points, 80 a shaft upon which the dial-arm is mounted and with which it is turnable, a pulley fixed upon the shaft with a weight whereby the dial-arm is held or returned to its normal position, an electric clutch, one member of which 85 is fixed to the dial-shaft and the other member to a sleeve turnable loosely upon said shaft, a mechanism whereby the clutch when energized is turned so as to rotate the dial-shaft, and means for deenergizing the clutch 90 so that the dial-shaft is released and the opposing weight acts to return the dial-arm to its normal position.

7. The combination with an electric motor and a mechanism moved thereby, of resist- 95 ance-coils connecting respectively with the armature and fields of the motor, switch-points arranged in circular segments and connecting with the resistance-coils, a dial-arm mounted upon a shaft centrally journaled between the 100 switch-points, whereby the dial-arm is movable over said points to increase or decrease the resistance in the motor-circuit, an electro- 105 magnetic clutch, one member of which is fixed to the shaft of the dial-arm, and the other member to a sleeve which is loosely revoluble upon said shaft whereby the two are united to move in unison when the clutch is energized, and allowed to move independently when it is deenergized, a weight acting to re- 110 turn the dial-arm to its normal position when the clutch is deenergized, a worm-gear connecting with the sleeve and the outer mem- 115 ber of the clutch, and a motor whereby the gear is driven so as to rotate the clutch and the dial-arm.

8. The combination with an electric motor and a mechanism driven thereby, of resist- 120 ance-coils connecting respectively with the armature and fields of the magnet, segmen- 125 tally-disposed switch-points upon opposite sides of a circle connecting respectively with the resistance of the armature, and that of the fields, a dial-arm mounted upon the central journal-shaft and turnable so as to suc- 130 cessively connect or cut out the resistance- coils, a weight by which the dial-arm is normally retained out of contact, a magnetic clutch one member of which is fixed to the dial-shaft and the other to a sleeve loosely rev- 135 oluble thereon, said sleeve being connected through the magnetic clutch when the latter is energized, so as to cause the dial-shaft to rotate with it, and disconnected therefrom when

the clutch is deenergized to allow the weight to return the dial-arm to its normal position.

9. The supplemental motor with wires connecting it with the switchboard of the elevator-cage whereby the motor may be thrown into or out of the circuit, and a worm-gear driven by said motor and connecting with the magnetic clutch so as to rotate the latter and the dial-arm while the motor is energized.

10. The combination with an electric motor and mechanism driven thereby, switch-points arranged in segments upon opposite sides of a circle and connecting with the resistance-coils respectively of the armature and fields, a dial-arm fixed upon a shaft which is journaled centrally between the segmental switch-points, whereby the opposite ends of the dial-arm are movable over the respective switch-points of the armature and field circuits to throw them out of and into the circuit, a magnetic clutch connecting with the shaft of the dial-arm to move the dial-arm in one direction over the switch-points when the clutch is energized, and a weight by which the dial-arm is returned to its normal position when the clutch is deenergized, a supplemental motor and intermediate mechanism whereby the clutch and dial-arm are turned so that the latter moves over the resistance switch-points to reduce the resistance in the main-motor circuit, an arm fixed upon the dial-shaft and a switch so fixed with relation to the said arm that the latter will move it when the dial-arm has reached the limit of its movement and disconnect the motor by which the clutch and dial-arm are actuated.

11. A rheostat having segmentally-disposed switch-points connected with the resistance-coils of the armature and the field, a dial-arm

pivoted and movable over the switch-points, an electromagnetic clutch mechanism by which the dial-arm is advanced over the switch-points when the clutch is energized, and means by which the dial-arm is returned to its normal position, when released, and a spring-actuated tip pivoted to the end of the dial-arm to maintain full contact with the conductor until the end of the dial-arm has passed, the spring acting to suddenly break the circuit and restore the tip to its normal position relative to the arm.

12. The dial-arm movable over the contact-plates of the armature and field circuits, a yielding extension of the dial-arm, and a stop by which it is maintained rigid with the arm when advancing, a contact-point connecting with the first contact-plate of the series of resistance-coils, and yielding to allow the extension of the dial-arm to pass when advancing, said extension itself yielding when it contacts with the point on its return, and maintaining a circuit through the point until it is broken suddenly by the action of its spring.

13. The dial-arm with its opposite ends movable over the contact-plates of the armature and shunt circuits respectively, a pin or stop connected with a plate of the shunt-circuit, against which that end of the dial-arm rests when it is in its normal position, whereby the field-circuit is first cut out when the arm returns to its position and a reconnection is instantaneously made with the field-circuit.

In witness whereof I have hereunto set my hand.

CHARLES M. WEYMAN.
